[57] CLAIM

The ornamental design for an automobile rear seat organizer, as shown and described.

DESCRIPTION

FIG. 1 is a top, rear, and left side perspective view of an automobile rear seat organizer showing my new design, the broken-line depiction of an automobile seat being for illustrative purposes only and forming no part of the claimed design;

FIG. 2 is a top, rear, and left side perspective view thereof, with the flap portion shown raised; and

FIG. 3 is a top, front, and right side perspective view thereof.

FIG. 1

FIG. 2

FIG. 3
